UNITED STATES PATENT OFFICE

LE ROI E. HUTCHINGS, OF TONAWANDA, NEW YORK, ASSIGNOR TO REMINGTON RAND
INC., OF BUFFALO, NEW YORK

INDEX DEVICE

Application filed March 27, 1930. Serial No. 439,508.

This invention relates to indexes or files of the overlapping visible card type and is more especially concerned with improvements in mounting such cards in an index tray or container.

Prior to the present invention cards or card holders of the type mentioned have either been mounted for oscillation or turning movement on an attached hinge member from which it was irremovable, or have been removably mounted on a wire or other metallic holder. The present invention comprehends improvements in the latter type of holders which have usually extended completely across the filing tray in slidable and removable relation thereto. The objection to the latter style of holder has chiefly been to its fragility as it has essentially been a resilient member. Such members have also been objected to because of difficulty in sliding them in a tray due to binding and the like, and a further objection has been to its susceptibility to accidental displacement due to violent jars on the tray or the like, also due to its resilient structure.

An object of the present invention is to provide separate hinge or mounting members for a card or card holder which may be manufactured to great accuracy in an easy and relatively economical manner.

A further object is to overcome the difficulties of the previous types of separate mounting means by providing a mounting member which does not depend upon resiliency for mounting in a tray but which may be removed therefrom in a simple manner.

Another object is to provide a mounting member to which may be pivotally mounted a number of separate cards or card holders which may be removable therefrom without disturbing the remaining cards mounted thereon.

A further object is to provide a novel form of metallic hinge member which is attached to the card to cooperate with the holder member.

Another object is to utilize the holding member as a retainer for a removably mounted index signal.

Another object is to provide for the cor-

rect pivotal mounting of extremely wide cards.

Other objects and advantages of the present invention are more specifically described in the accompanying drawings and specifications.

In the drawings:

Fig. 1 is a perspective view of a tray incorporating the novel card mounting of the present invention.

Fig. 2 is a cross-section through such tray.

Fig. 3 is a partial elevation of the tray showing the double card mounting on the holder of the present invention.

Fig. 4 is a perspective view of the preferred embodiment of the holder member.

Fig. 5 is a perspective view of the preferred embodiment of the bearing member.

Fig. 6 is a section on the line 6—6 of Fig. 3.

Fig. 7 is a perspective view showing the holding action of the shoulders of the bearing member.

Fig. 8 is an elevation showing the use of a signal member with the holder of the present invention.

Fig. 9 is an elevation of a card holder provided with the bearing member of the present invention.

Fig. 10 is a side elevation of Fig. 9.

Fig. 11 is an elevation of a card mounted in a tray and having three supports.

Fig. 12 is a perspective view of a permanent type bearing member.

Fig. 13 is a section through a card and attached permanent type bearing member.

In the drawings, the numeral 1 designates a container or tray which is preferably a thin flat structure having flanged sides 2 and a handle-carrying front portion. Within the tray is secured a bottom member 3 which is of sheet-metal construction comprising attaching legs 4 welded to said tray and an integral raised portion 5 arranged longitudinally and centrally of the tray. The bottom member extends for substantially the full length of the tray. The shoulders 6 of said bottom member are utilized as spacers for the retainers or holder panels 7 which abut said shoulders and are welded to the legs 4. The flanges 8 of the holder panels, which are pref-

100

erably U-shaped extensions thereof, are adapted to contain transversely therebetween the holder members 10 which are preferably sheet-metal stampings, each having a flat base 11 rectangular in shape and adapted for easy sliding movement in said holder panels. The corners of the base 11 are rounded to allow the holder members to be inserted in the holder panels by an angular sliding movement. The holder members are clamped in the holder panels 7 with their base portions in contacting relation in any suitable manner and with the holders in one panel in alignment with the holders in the opposite panel. 15 In the preferred form of holder member two lugs 12 and 12' are shown struck from the base 11 and comprising integral vertical and horizontal portions, the horizontal portions thereof being shouldered and narrowed near 20 their extremities to form pintles 13 and 13' respectively.

It will be understood that the form of member shown as in Fig. 1 is exemplary and that any number of pintles may be used on the 25 holders. The pintles on the holder member in opposite holder panels in the tray shown in Fig. 1 point centrally and form pairs of aligned holder members containing pintles at each side of the tray pointing centrally. 30 The outer pintles 13 of each pair removably receive a record-containing member or card 15. The card is provided with means to co-operate with said pintle and form a bearing therewith.

35 Fig. 5 shows one form of such means which comprises a bearing member 16 having a cylindrical journal portion 17 and a flat portion 17' integral therewith and extending therefrom and having a reduced end portion 18 forming shoulders 19 on said flat portion. The reduced end portion 18 turns back upon 40 said flat portion and tapers at its extremity to form an entry clip 20 which resiliently rests against the journal 17. The card 15 contains narrow slots 21 of approximately the same 45 width and thickness as the reduced end 18 in which the entry clip 20 is adapted to be removably entered so that the portion between slot 21 and the end of the card is wholly received between the journal 17 and the bent-back end portion 18 of the bearing member. The card is removable from the bearing member by a reversal of this process. 50 When used with the tray of the type shown, the cards are often subjected to violent shocks caused by the slamming of the trays in their container or cabinet. The recoil of such handling has been found to be sufficient to displace a card from a spring clip and the shoulders 19 of the bearing member are provided to prevent such displacement.

Fig. 7 shows the action of a card under rearward urge, and it will be seen that the lip or edge of the slot 21 upon such rearward 55 movement engages upon and is retained by

the shoulders 19 and the bearing members, thus preventing accidental displacement. As shown in Fig. 1, the card 15 is provided with two bearing members 16 which are adapted to register with and enter upon the outer pintles 13 of a pair of holder members. 70

The second set of pintles 13' upon the same set of holder members is adapted to receive the bearing members 16 of the second card 23 which is of the same shape and size as the card 15 and which on its free edge contains a cut-back portion 24 forming a tab 25 on the remaining portion of the edge of the card. Thus, with the double pintle holder shown, two overlapping cards may be mounted upon the same set of holders with portions of both cards exposed along their free margins. Fig. 2 shows the method of inserting a card upon such pintle members wherein the card is flexed as shown at 22 to permit entry of the journals 17 in their respective pintles. Upon the release of the card in such flexed position, the assembly of the journal 17 with the pintle will be maintained and the cards will be swingable about the bearings thus 90 formed. Each card is thereby removable from its supporting pintles without displacement of the remaining card in the same 95 holders.

The spacing of the cards which determines 100 the overlap between adjacent groups of cards mounted on the same set of holders is determined by the width of the base 11 of the holder members. Thus upon requirement of visible card margins of greater width, holder members having bases of greater width may be inserted in the holder panel 7 to change the spacing of the visible portions of the 105 cards.

The arrangement of the holder member 105 and the interspaced raised portion 5 is intended to give a substantially level surface to support the card for the purposes of enabling and facilitating the making of entries direct upon the mounted cards without removal 110 thereof.

Fig. 8 shows a further use of the double pintle holder. In this embodiment a signal member 27 which is preferably a sheet of colored celluloid is of a width narrower than 115 the underlying card 15. The inner pintles 13' in this case are utilized as mounting means for such signal and as the signal 27 is of the same width as the card 15, the free marginal portion thereof will project into 120 the visible space when the cards are in overlapping stepped position and provide signal means which are utilized in bookkeeping systems and the like in a well-known manner.

Fig. 9 shows a pair of bearing members 16 applied to a card holder for the purpose of 125 mounting the same in a tray in the same manner as the card 15 of Fig. 1. This member, aside from the mounting means thus provided, is similar in function to the type of 130

index device disclosed in Rand, No. 1,622,670, March 29, 1927 having at its free extremity a pocket such as a celluloid sheath for receiving a record card or index signal.

5 On extremely wide cards three or more holders may be used. Fig. 11 discloses the use of an additional holder panel 7' which contains an extra set of holder members having pintles for engaging the central portion of a wide card 28. In this variation the holders preferably contain but one pinte 13" and the two pintles on the left of the set illustrated are arranged to point toward each other, while the pinte at the right is engageable from the left. The method of inserting 10 a wide card on this pinte is to first engage the bearing members 16 in the two opposed pintles first described and to then lock the card in place by the engagement of the bearing member with the pinte at the right.

20 Other forms of bearing members may be used. The preferred embodiment discloses a removable member. It is found, however, that certain types of installations may preferably use a permanently secured type of bearing member. The form shown in Fig. 12 shows a fixedly secured bearing member 29 which is similar to the bearing member 16 with the exception that the entry clip 20 is substituted for by an inturned portion 30 which is engaged through the slot 21 of a card and is then bent downwardly to a position in close proximity to the flat body portion of the bearing member, thereby permanently securing the card to the bearing member.

30 The invention above described may be modified in construction and arrangement without departing from the invention as defined in the appended claims.

40 What is claimed is:-

1. The combination with a filing tray having spaced retainers mounted therein, of a series of holder members removably mounted in each of said retainers, each holder member having an extending pinte, said holder members on opposite retainers being aligned with their respective pintles extending toward each other, bearing members rotatably mounted on said pintles, and a flexible card mounted on said bearing members, said card maintaining said bearing members on said pintles.

2. The combination with a filing tray having a plurality of spaced longitudinally arranged card holder retainers, of a series of card holders in each of said retainers, each of said card holders in one retainer being in transverse alignment with a corresponding card holder in the remaining retainers, and a card rotatably and removably mounted on each aligned pair of card holder members.

3. The combination with a filing tray having spaced retainers mounted therein, of holder members each having a flat base por-

tion removably mounted in each of said retainers and having horizontal pinte portions, the holder members in opposite retainers being aligned with their respective pinte portions extending laterally of the tray toward each other to form sets of holder members, a card rotatably and removably mounted on the outer pintles of each set and a second card overlapping said first-named card and rotatably and removably mounted on pintles in the same set adjacent said outer pintles.

4. The combination with a filing tray having spaced retainers mounted therein, of holder members removably mounted in each of said retainers, each holder member having pinte portions, the holder members in opposite retainers being aligned with their respective pinte portions extending laterally of the tray toward each other to form sets of holder members, a card rotatably and removably mounted on the outer pintles of each set, and a signal member rotatably and removably mounted on the remaining pintles in each of said set of holder members, said signal member having a free marginal portion arranged in substantially aligned relation to the free marginal portion of said card.

5. The combination with a filing tray having spaced retainers mounted therein, of holder members each having a flat base portion removably mounted in each of said retainers and having horizontal pinte portions, the holder members in opposite retainers being aligned with their respective pinte portions extending laterally of the tray toward each other to form sets of holder members, a card rotatably and removably mounted on the outer pintles of each set and a second card overlapping said first-named card and rotatably and removably mounted on pintles in the same set adjacent said outer pintles, the cards in one set of holder members overlapping the cards in an adjacent set of holder members with marginal portions exposed.

6. The combination with a filing tray having a plurality of retainers mounted therein, of holder members removably mounted in said retainers in transverse aligned relation with each other relative to said tray, each holder member having a pinte portion, and a card rotatably mounted on the pintles of each aligned group of holder members.

7. The combination with a filing tray, of holder members mounted in said tray and having pinte portions extending inwardly from opposite sides of the tray, a bearing member comprising a journal portion rotatably mounted on each of said pintles, a flat portion extending from said journal and a turned-back portion resiliently engaging said journal portion; and a card having spaced slots at one margin, said turned-back portions of said bearing members being mounted through said slots in said card to retain the

marginal portion of the card between said flat portion and said turned-back portion.

8. An index device comprising, a card having a slot adjacent one margin; a bearing member having a journal portion, a flat portion extending therefrom and a turned-back end thereof engaging said journal portion; said end extending through the slot in said card and retaining the marginal portion of

10 said card on said flat portion.

9. An index device comprising a card having a slot adjacent one margin; a bearing member having a journal portion, a flat portion extending therefrom and a turned-back end thereof overlying and resiliently engaging said journal portion; the marginal portion of said card being removably mounted between said end and said flat portion, with the slot in said card being entered by said end.

15 10. An index device comprising a card having a slot adjacent one margin, a bearing member having a journal portion, a flat portion extending therefrom, with shoulders at the end of the same, and a turned-back end 20 thereof overlying and resiliently engaging said journal portion; the marginal portion of said card being removably mounted between said end and said flat portion with the slot in said card being entered by said end,

25 30 said shoulders engaging the margin of the slot in said card.
